(57) **CLAIM**

(21) Appl. No.: **29/232,042**

The ornamental design for a surround sound speaker for a personal computer, as shown.

(22) Filed: **Jun. 13, 2005**

DESCRIPTION

(51) **LOC (8) Cl.** **14-01**

FIG. 1 is a front elevation view of the invention illustrating my design;

(52) **U.S. Cl.** **D14/216**; D14/213

FIG. 2 is a rear elevation view thereof;

(58) **Field of Classification Search** D14/204,

FIG. 3 is a left side elevation view thereof;

D14/207, 209–216; 181/143–144, 147–148,

FIG. 4 is a right side elevation view thereof;

181/150, 157, 198–199, 151, 153; 381/300–302,

FIG. 5 is a top plan view thereof;

381/306, 333, 345, 361–364, 386–388, 332,

FIG. 6 is a bottom plan view thereof; and,

381/336

FIG. 7 is a front perspective view thereof.

See application file for complete search history.
